PIN-RECEIVING TAB FOR GARMENTS.

1,353,930.

Specification of Letters Patent. Patented Sept. 28, 1920.

Application filed February 16, 1920. Serial No. 359,063.

To all whom it may concern:

Be it known that we, HERMAN MERKEL and JACOB BUECHER, citizens of the United States, and residents of East Orange, county 5 of Essex, and State of New Jersey, and Newark, county of Essex, and State of New Jersey, respectively, have invented certain new and useful Improvements in Pin-Receiving Tabs for Garments, of which the 10 following is a specification.

This invention relates to an improved tab to be attached to garments and which provides means for receiving a pin, this being usually done in the attachment of hose supporters to under-waists, particularly for 15 children's wear.

The invention consists in a tab of this kind which is adapted to be supplied to the operator for attachment to the waist, the 20 tab consisting of a strip and also a pin receiving member, the strip being held against movement relative to the member so that it can be easily attached to the garment.

Another advantage of the device is that 25 the strip can be threaded or passed into a slit or eye in the pin receiving member much easier than in forms heretofore employed, and after being so threaded, a slight manipulation of a part of the pin receiving 30 member holds the strip so that all parts of the strip are held in engagement with the slit in which the strip is threaded, so that the bunching or wrinkling of the strip into one corner of the slit through which it 35 passes is prevented, so that an oblique disposition of the pin receiving member relative to the garment is prevented.

As heretofore made there have been two serious defects in this class of goods, one 40 being that the strip part of the tab rides up into one corner of the slit in the pin receiving member, and the other is that the threading of the material of the strip into the slit of the pin receiving member has 45 been difficult and necessarily slow and therefore expensive, an operator taking a great deal of time threading this short strip of tape into the slit, thus making a comparatively expensive step in the assembling of 50 what is a small part of the finished garment.

Our invention therefore comprises an article of manufacture which is a tab ready for attachment to the garment, the strip of the tab being threaded into the pin receiving 55 member with speed and ease, due to the construction, and after its insertion it is held flat in the slit so that the ends of the strip

are substantially even, and an operator fastening these tabs to under-waists has no difficulty in assembling the parts and securing them together.

The invention is illustrated in the accompanying drawing, in which Figure 1 is a front view of an improved tab made according to our invention, with the edge of the under garment and the upper part of the hose supporter shown in dotted outline. Fig. 2 is an edge view of the tab shown in Fig. 1, with the pin receiving member shown in section, and Fig. 3 is a perspective view with the strip of fabric placed in the slit of the pin receiving member and showing the lip of the pin receiving member in the position it occupies before it is pressed down to hold the strip against longitudinal or lateral movement. Fig. 4 is an enlarged section of the device.

In the drawing 10 indicates the bottom edge of a garment, such as a child's under-waist, and 11 the top end of the strip of a 80 hose supporter provided with a safety pin 12 on its upper edge, the bar 13 of the pin being adapted to be received in the pin receiving member of our improved tab.

The tab comprises a strip 14 of fabric, 85 usually muslin, which is fastened, by stitching 15 or by other means, to a garment and which serves to suspend from its bottom edge a pin receiving member, which is a metal clip bent up from sheet metal to form 90 the tubular part 16 which receives the pin 13 and has an ear 17 provided with a slit 18 as wide as, or slightly wider than, the strip 14, a non-cutting top edge of the slit being provided by folding over the material 95 punched out of the ear to provide for the slit against the face of the ear, as at 19. This forms a double rounded edge which does not tear the material of the strip 14.

We prefer to make the pin receiving member of one piece of metal, the ear 17 projecting from the tubular part 16, and closely adjacent thereto we provide a lip 20. This lip, as shown in Fig. 2 in dotted outline and in Fig. 3 in full lines, is bent away on its top 105 edge from the slit 18, preferably in a slight curve. When the pin receiving member is in this shape the strip 14 is easily threaded through it, since when the end of the strip is started in from the rear side of the clip 110 it can be done by hand and requires no threading instrument, because the front end of the strip will hit the curve on the inner face of the lip 20 and thus be fed upwardly

so that it can be readily grasped after it is passed through the slit, and these short strips of fabric can be placed into the pin receiving members comparatively cheap because many can be finished in a very short time. After the strip 14 is in place the lip 20 is bent down, either by hand or by a suitable tool or machine, to assume the position shown in full lines in Fig. 2, and shown 10 more fully in Fig. 4. When so bent, the lip engages the strip 14 at the edge of the slit 18, and the opposed faces that thus embrace the faces of the strip do not cut or tear the strip, but there is sufficient pressure to prevent the strip from being bunched or 15 wrinkled, and in this way the usual gathering of the strip in one end of the slot is prevented and the tubular member is always held substantially parallel to the bottom 20 edge of the garment, this in turn equalizing the strain on all parts of the pin 13.

The lip can be positively seated in the slit by being indented, as at 21, which indentation closely engages the strip of fabric for 25 practically its full width, either continuously or at separated points, thus insuring the flat disposition of the strip of fabric. This indentation is more clearly set forth in Fig. 4, and it can extend, as shown in Fig. 30 1, so that its indented portion takes up such part of the slit as is not occupied by the fabric, makes a substantially smooth outer surface and the end of the lip does not unduly project.

35 We claim:

1. A pin receiving tab for garments com-

prising a strip of fabric, a tubular clip having a slotted ear to receive the strip, and means for insuring the engagement of the strip for its entire width with the edge of 40 the slit.

2. A pin receiving tab for garments comprising a clip formed into a loop with an ear extending therefrom, the ear having a 45 slit therein, a strip of fabric folded in the slit, and a lip on the clip and disposed so as to engage the fabric adjacent to the slit so that the fabric is prevented from becoming bunched.

3. A pin receiving tab for garments comprising a clip formed into a loop with an ear extending therefrom, the ear having a 50 slit therein, a strip of fabric folded in the slit, and a curved lip with its upper end outwardly bent opposite the slit so that said lip 55 can be bent to engage the fabric to hold it flat at its fold.

4. A pin receiving tab having a clip thereon, the clip being formed into a long loop with an ear extending therefrom, the ear 60 having a slit parallel with the loop, and a lip bent outwardly from the juncture of the loop and the ear, in combination with a strip of fabric folded in the slit, the lip being bent down to hold the strip of fabric 65 straight in the slit for its entire width.

In testimony that we claim the foregoing, we have hereto set our hands, this 13th day of February, 1920.

HERMAN MERKEL.
JACOB BUECHER.
